UNITED STATES PATENT OFFICE

CHARLES L. ELLIS, OF BRADFORD HILLS, PENNSYLVANIA, ASSIGNOR TO DOWNTOWN MANUFACTURING COMPANY, OF DOWNTONTOWN, PENNSYLVANIA, A CORPORATION OF PENNSYLVANIA

BOARD MACHINE

Application filed October 16, 1930. Serial No. 489,215.

PROPOSED

This invention relates to cylinder paper machines, and more particularly to an apparatus for transferring the formed paper web from the wet end of such machines to the 5 press section of the machine.

An important object of the invention is to provide a structure delivering the paper web or sheet formed on the cylinder molds to the first press in a much drier condition than has 10 heretofore been possible and to attain this result without the use of the usual primary press rolls.

A further object of the invention is the provision of a structure of this character eliminating the use of one of the usual long felts with its accompanying equipment of felt rolls, guide rolls, stretchers, whippers and the like, thereby reducing the power required in operation and eliminating the losses due to the 20 deterioration of such felts.

A further and more specific object of the invention is the provision of a structure of this character wherein the paper web or sheet is delivered to an endless carrier preferably 25 consisting of a wire by means of which it is transferred to the first press, the sheet while on the carrier being subjected to the action of a suction roll or rolls.

A further object of the invention is to provide in a construction of this character an arrangement such that the pick-up felt and web after leaving the last cylinder of the machine may be acted upon by an extractor press so that when the felt moves to deliver the web 30 to the endless carrier such web is dried to an extent that any extensive press action is unnecessary before the web is delivered to the drier.

These and other objects I attain by the construction shown in the accompanying drawings wherein, for the purpose of illustration, I have shown a preferred embodiment of my invention and wherein:

Fig. 1 is a side elevation of a cylinder paper 45 machine illustrating a portion of the cylinder and press parts thereof and the intermediate transfer mechanism;

Fig. 2 is an enlarged diagrammatic view of the transfer mechanism;

Fig. 3 is a fragmentary diagrammatic view

showing a possible modification of the arrangement of Figs. 1 and 2;

Fig. 4 is a semi-diagrammatic view illustrating a modification of the arrangement of Fig. 1 to include the use of an extractor press; 55

Fig. 5 is a view similar to that of Fig. 4 illustrating the substitution of a felt for the wire as an endless carrier; and

Fig. 6 is a fragmentary detail view showing the construction of the bottom roll of the 60 extractor press.

Referring now more particularly to the drawings, and more particularly to Figs. 1 to 3 thereof, the numeral 10 indicates a cylinder vat which may constitute the solitary vat 65 of the machine or the final of a series of such vats. This vat has arranged therein the usual cylinder mold 11 upon which operates a couch roll 12. In spaced relation to the vat 10 is disposed a final press section 13. Between the vat 10 and the final press section 13 I dispose a transfer mechanism generally designated at 14 including a wire 15 passing over an end wire roll 16 of any ordinary or usual construction, arranged adjacent the vat, 70 through a suction press comprising a transfer suction roll 17 and an imposed top roll 18 therefor, over an end roll 19, preferably a suction roll, disposed adjacent the press 13 and then back to the end wire roll 16, this 75 stretch of the wire having associated therewith the usual stretch roll 20 and wire guides 21 and 22 which may be of the type ordinarily employed in such location.

The pick-up felt 23 of the vat end of the machine passes over the wire from the end wire roll 16 to the suction press roll 17 from which point it is returned over the top press roll 18 to the vat end of the machine. The 80 paper web or sheet W picked up by the cylinder mold is transferred to the felt 23 and passes with this felt over the wire to the suction press roll 17. By this roll it is transferred to the wire and from this point moves with the wire to the suction end roll 19 where it is again subjected to the action of suction and transferred to the press end of the machine. Instead of the usual suction roll, as 85 illustrated in Figs. 1 and 2, a suction roll having a porous, resilient covering 17—a may be 90

100

employed if so desired. This covering will tend to shield the wire from the rapid wear ordinarily resulting when the wire is passed directly over a suction roll.

- 5 8 Use of apparatus of this character in transferring the paper web W from the cylinder to the press end of the machine results in the production of a sheet free from felt marks which can be produced at a much higher speed 70
10 and with much less pressing and expenditure of power than is ordinarily necessary. Furthermore, the losses due to shrinkage with a construction of this character are materially reduced. 75
15 The structure just described is that set forth in my prior application, Serial No. 462,561 for patent on multi-cylinder board machine, which was filed June 20, 1930, and of which application this application is in 80
20 part a continuation. In Fig. 4 I have illustrated a modification of the foregoing structure wherein, instead of depending upon the suction press, designated by the upper and lower rolls 17 and 18, for the removal of such 85
25 a quantity of water as it will necessarily remove with the arrangement shown in these figures, I provide between the final cylinder mold and said suction press an extractor press 24 comprising a lower or extractor roll 25 and 90
30 an associated upper press roll 26. This extractor press acts upon the felt 23 before it joins the endless carrier, the pulp web or sheet W coming in contact with the extractor roll 25. This roll is constructed somewhat 95
35 similarly to a cylinder mold but is more strongly made in order that it may withstand the heavy pressures placed thereon, comprising a skeletal cylindrical frame 27 and a wire cloth covering 28 therefor. At this time 100
40 there is only associated with the paper web the felt 23 with the result that the extractor press removes considerable water from both the felt and the paper web, some of this water passing through the surface of the extractor 105
45 roll 25 while the remainder thereof collects between the rolls 25 and 26 and is deflected by 110 a slice 29. The wire covering of the extractor roll, not having the same affinity for the paper web as the felt, does not remove the web from 115
50 the felt but permits it to continue with the felt until it passes through the suction transfer press consisting of the rolls 17 and 18. The suction transfer press removes further water and serves to separate the paper web 120
55 from the felt, which felt returns over the top of the cylinder mold or molds to again begin 125 its pick-up travel while the web moves over the endless carrier to the final press 13. The extractor press 24 removes a very considerable amount of water from the paper, this amount generally being between one and one-half (1½) and two (2) tons per ton of paper finally produced by the machine. Due to the amount of water removed by the extractor 130
60 press, a press felt may be substituted for the 135

wire in a construction of this character if so desired, this arrangement being suggested in Fig. 5, the sole changes necessary to this arrangement being the provision of a take-up for the felt 9—a as suggested at 30. It will be noted that in each of the constructions the use of a long felt is eliminated with its associated mechanisms, thus materially reducing the actual cost of construction of the board machine and since the paper web produced may be delivered to the driers with a much smaller water content and at a much higher rate of speed than is possible with the ordinary machine, the efficiency of the entire organization is materially increased. 140

Since the structure hereinbefore set forth is but one of a number which might be adapted without departing from the spirit of my invention, I do not wish to be understood as limiting myself thereto except as hereinafter claimed. 145

I claim:

1. The combination with a cylinder board machine including the usual endless felt receiving the wet pulp from the cylinder mold, of an endless wire over which the felt passes and a pair of transfer press rolls between which the felt, the pulp and the wire pass, said transfer press rolls being so constructed and arranged that the pulp is transferred from the felt to the wire. 150

2. In a cylinder board machine having the usual endless pick-up felt and press end, means for transferring the pulp to the press end comprising an endless wire and a press including a suction roll acting through the wire for transferring the pulp from the felt to the endless wire. 100

3. In combination with a cylinder board machine comprising a wet end having the usual pick-up felt and the usual main press section, an endless wire receiving the pulp from said pick-up felt and transferring it directly to the main press section, and at least one suction roll associated with said endless wire to act upon the pulp through the wire during its passage thereover and to assist in the transfer of the pulp from said pick-up felt to the wire. 105

4. In combination with a cylinder board machine comprising a wet end having the usual pick-up felt and the usual main press section, an endless wire receiving the pulp from said pick-up felt and transferring it directly to the main press section, and a plurality of suction rolls associated with said wire to act upon the pulp through the wire during its passage thereover, one of said suction rolls assisting in the transfer of the pulp from the pick-up felt to the wire. 115

5. The combination with a cylinder paper machine including the usual endless felt for receiving the wet pulp from the cylinder mold, of an endless wire and a suction press through which the wire, the pulp and the felt 120

pass with the wire contacting directly with the suction roll of said press, whereby the pulp is transferred to the endless wire, said suction roll having a porous resilient jacket.

- 5 6. The combination with a cylinder paper machine including the usual endless felt for receiving the wet pulp from the cylinder mold, of an endless wire over which the felt passes, a pair of transfer press rolls between
 10 which the felt, the pulp and the wire pass, whereby the pulp is transferred to the wire, and an extractor press between the rolls of which the felt passes prior to joining the wire.
- 15 7. The combination with a cylinder paper machine including the usual endless felt for receiving the wet pulp from the cylinder mold, of an endless wire, a press including a suction roll over which the wire, the pulp
 20 and the felt pass with the wire contacting directly with the suction roll, whereby the pulp is transferred to the endless wire, and an extractor press between the rolls of which the felt passes prior to joining the wire.
- 25 8. In combination with a cylinder paper machine and a wet end having the usual pick-up felt and the usual press section, and endless wire receiving the pulp from said pick-up felt and transferring it directly to the press end
 30 of the machine, at least one suction roll contacting directly with said endless wire to act upon the pulp during its passage thereover, and an extractor press between the rolls of which the felt passes prior to joining the
 35 wire.

9. In combination with a cylinder paper machine and a wet end having the usual pick-up felt and the usual press section, an endless wire receiving the pulp from said pick-up felt
 40 and transferring it directly to the press end of the machine, at least one suction roll contacting directly with said endless wire to act upon the pulp during its passage thereover and to assist in the transfer of the pulp from
 45 said pick-up felt to the wire, and an extractor press between the rolls of which the felt passes prior to joining the wire.

10. In a paper machine, a pulp web-forming mechanism including a pick-up felt, a
 50 press section toward which the operative run of the felt moves, an extractor press through which the felt and its attached web pass immediately after completion of the pick-up run, an endless wire for transferring the web
 55 directly to the press section and means for transferring the web from said felt to the wire, including a suction roll with which the wire is in direct contact acting through the wire, the web, and the felt.

60 CHARLES L. ELLIS.
